UNITED STATES PATENT OFFICE.

FRANK JAY ANDREWS, OF HOLDEN, ALBERTA, CANADA.

ADJUSTABLE COWL FOR SMOKE-STACKS.

1,013,358.

Specification of Letters Patent.

Patented Jan. 2, 1912.

Application filed April 11, 1911. Serial No. 620,467.

To all whom it may concern:

Be it known that I, FRANK JAY ANDREWS, a subject of the King of Great Britain, residing at the town of Holden, in the Province of Alberta, Canada, have invented certain new and useful Improvements in Adjustable Cowls for Smoke-Stacks, of which the following is a specification.

My invention relates to improvements in adjustable cowls for smoke stacks, and is more particularly designed to be used in connection with smoke stacks for traction engines, and the principal object of my invention is to combine with a smoke stack, an adjustable cowl which will act as a wind brake, and so prevent the current of air from striking the products of combustion as they escape from the stack. As the said cowl is substantially semi-circular, when properly positioned it will shield the top of the smoke stack, and so effectually prevent the creation of wind pressure in and at this point, and so insure the ready and free escape of the products of combustion from the stack and their quick removal, thus materially increasing the draft through and from the fire box, with resultant self-evident advantages.

Another object of my invention is to provide a particular construction of means for supporting and manipulating the cowl.

A still further object of my invention is to construct the attaching means for my cowl so that a spark arrester may be readily placed in position and removed from the stack, and the construction of my preferred form of invention, will be hereinafter particularly set forth, and the parts I claim as new will be pointed out in the claims forming part of this specification.

Figure 1 is a side elevation of a smoke stack, and portion of the boiler therefor, showing my cowl and operating means attached to the stack, and also showing the means whereby the operator shifts the position of the cowl. Fig. 2 is a plan view of the stack and the parts carried thereby illustrated in Fig. 1, and Fig. 3 is a vertical cross section on the line *a—b*, Fig. 1, on an enlarged scale.

In the drawings, like characters of reference indicate corresponding parts in each figure.

The cowl I use will extend above the top

of the smoke stack, approximately for one-third of the height of the stack, and as it is semi-circular in horizontal cross section it will act as a wind brake for the whole upper surface of the smoke stack, thus preventing the wind from striking against any portion of the inner edge of the smoke stack, resulting in the advantages before set forth. As the cowl is readily adjustable, it can be moved as the wind shifts so as to occupy the most effective position. As will be herein-after more particularly set forth, the said cowl is so constructed as to permit of its ready removal from the smoke stack should conditions demand this.

Although my invention is designed to be used more particularly in connection with the smoke stacks for traction engines, and the like, still it is self-evident that it may be employed in connection with stationary smoke stacks.

In the north-western territories and provinces of Canada, straw is very largely used as a fuel, and from actual test I have found that on very windy days, particularly if the straw be damp, which is often the case, it is very difficult to maintain the necessary steam pressure unless I use a cowl. With the use of the cowl I found it not only easy to maintain the necessary steam pressure, but I also found that I could get up steam much quicker than without it.

A is the smoke stack and B the boiler supporting the same. The ring plate C will of course be made to fit the smoke stack more or less snugly, and the same is integrally provided with a flange D.

E are a plurality of brackets which are bolted by the nuts and bolts F to the smoke stack A. The upper ends of these brackets are secured by the nuts and bolts G to the flange D. Of course any suitable means may be used by me to attach the ring plate C in place. The brackets E will preferably be constructed so that they may be bent as conditions demand in fitting the ring plate C in place. Integrally formed with the ring plate C is an annular step 2, and integrally formed also with said ring plate is an annular collar 3 which projects above the said step. The said ring-plate constructed as described, is the base or foundation for supporting the cowl and its immediately-associating operating parts.

4 is a toothed-ring plate which rests upon and is carried by the annular step 2, and the vertical portion of the ring-plate 4 is made in the form of an annular collar or ring 5 which projects above the annular collar 3. The annular collar or ring 5 is divided into an annular flange 6 which is spaced apart from the supporting-plate 7 preferably integrally formed with said annular collar or ring 5. By reason of preferably integrally forming the supporting-plate 7 with the ring 5, I preferably form an annular flange 8 integrally with said ring 5 so that the same may project beyond the inner surface of the said ring 5, and so provide sufficient material at the base of the supporting-plate 7 for the purpose of giving this plate firm support from the annular collar or ring 5.

9 is the cowl, and same is substantially semi-circular in horizontal cross section. This cowl occupies the position illustrated particularly in Fig. 3, wherein it is shown as resting upon the inner portion of the annular collar 3 so as not to overhang any part of the wall of the stack A. This position of the cowl enables me to place in position and readily remove a spark arrester, for instance the spark arrester 10 shown in dotted lines in Fig. 3. The upper edge of the stack A forms a shoulder 11 on which rests the flange 12 of the spark arrester. The attaching means for the cowl 9, herein-after particularly described, is also out of the path of movement of the spark arrester.

Passing through a hole formed in the annular collar or ring 5 is a bolt 12', intermediate the head 13 of which and the cowl 9 is a plate 14 used to increase the thickness 40 of the metal of the cowl where the bolt 12' passes therethrough.

15 is a thumb-nut screwing on the outer end of the bolt 12'.

By the means just described, the cowl can 45 be firmly held in place and in case it should be necessary to remove the same, this can be readily done.

The supporting-plate 7 is preferably of the shape shown particularly in Fig. 1, as 50 this shape while giving ample support to the cowl 9, does not unnecessarily increase the weight to be carried by the ring-plate C.

16 and 17 are standards secured by nuts and bolts, or other suitable fastening means, 55 to the ring-plate C, and held in bearings in these standards is a worm-shaft 18. Mounted on this worm-shaft and between said standards is a worm 19 which engages with the teeth 20 of the toothed-ring-plate 4 and 60 moves this ring-plate when turned. By reason of the annular step 2, I am enabled to position the worm 19 above the flange D of the ring-plate C so as to allow freedom of movement for this worm, and permit the 65 parts to be easily and readily assembled.

A sprocket-wheel 21 is keyed to the worm-shaft 18 and this wheel is connected by a sprocket-chain 22 to the sprocket wheel 23 keyed to the shaft 24 provided with an operating crank 25.

26 is a bearing carried by the boiler in which shaft 24 operates.

27 is a block-bearing in which the outer end of the shaft 24 has bearing. This block is a casting, clamped to the side of the smoke-stack A by means of the rod 28 which passes around said smoke-stack, its ends passing through holes formed in said bearing block in which position they are anchored by the nuts 29 and 30. Now by 80 manipulating the crank 25, it will be readily understood from the foregoing specification how the cowl 9 can be moved into the desired position, without further explanation.

The standards 16 and 17 are each provided with an overhanging lip 31 which occupies the position shown in Fig. 3 overhanging the inner side of the annular flange 6.

32 are a pair of brackets carried by the flange D, and these brackets are also each provided with an overhanging lip 33 which overlaps the annular flange 6 as shown in Fig. 3. The brackets 32 together with the standards 16 and 17 prevent the displacement of the toothed-ring-plate 4, as will be understood. The passage of the traction engine over a rough road will of course subject the before-mentioned parts to considerable jarring, and in order to prevent any 100 displacement of the parts described, I have provided the means already set forth.

Of course the plate 14 may be integrally formed with the cowl 9, if desired.

I do not confine myself to the construction herein shown and described, except in so far as that may be rendered necessary by the prior state of the art and the terms of my claims.

What I claim as my invention is:

1. The combination with a smoke-stack, of an outside placed supporting member supported by the stack near the top thereof; means securing said supporting member to the stack; a toothed ring-plate carried by said supporting member and surrounding the stack; a cowl substantially semi-circular in horizontal cross section detachably carried by said toothed ring-plate; means for detachably securing said cowl in place, and supporting the cowl outside of the internal horizontal diameter of said smoke stack; a toothed member co-acting with said toothed ring-plate in order to move same to shift the position of said cowl; bearing members supported by said supporting member in which said toothed member has bearing; means for operating said toothed member, and means carried by said supporting member and engaging said toothed ring.

plate in order to hold the same in proper relationship to said supporting member, as and for the purpose specified.

2. The combination with a smoke stack, of 5 an outside-placed supporting member supported by the stack near the top thereof; means securing said supporting member to the stack; a toothed ring-plate carried by said supporting member surrounding the 10 stack the said toothed ring-plate being integrally provided with an annular flange at its upper portion, and being further integrally provided with a supporting plate spaced apart from said annular flange; a cowl 15 formed substantially semi-circular in horizontal cross section positioned against said supporting-plate, means carried by said toothed ring-plate for holding said cowl in position against said supporting plate and 20 outside the internal horizontal diameter of said smoke stack, a toothed member co-acting with said toothed ring-plate in order to move same to shift the position of said cowl; bearing members supported by said sup- 25 porting member in which said toothed member has bearing; said bearing member pro- vided with lips overhanging the annular flange of said toothed ring-plate, and means carried by said supporting member and 30 constructed to overhang the annular flange of said toothed ring-plate, as and for the purpose specified.
3. The combination with a smoke-stack; a ring-plate integrally provided with a horizontal flange and further integrally pro- 35 vided with an annular step and an annular collar projecting above and positioned within, said step, the said ring-plate designed to be placed around a smoke stack with its an- 40 nular collar fitting thereagainst; means de- tachably secured to said horizontal flange
- for securing said ring-plate to said smoke stack; a toothed ring-plate resting upon said annular step and surrounding said annular collar and integrally provided at its upper 45 portion with an annular flange; a cowl sub- stantially semi-circular in horizontal cross section carried by said toothed ring-plate outside the horizontal diameter of said smoke stack; a supporting plate carried by said 50 annular flange for supporting said cowl; de- tachable means carried by said annular flange for the purpose of securing said cowl in place; two standards carried by the flange of said ring-plate, and each provided at its 55 upper end with a lip which overhangs the annular flange of said ring-plate; a worm- shaft having bearing in said standards; a worm mounted on said shaft and po- sitioned between said standards and above 60 said horizontal flange and in engagement with the teeth of said ring-plate; means for operating said worm-shaft, and means car- ried by said horizontal flange and overhang- 65 ing the annular flange of said ring-plate, as and for the purpose specified.
4. The combination of a toothed-ring- plate integrally provided with a vertical annular flange, and further integrally pro- 70 vided with a vertically-disposed supporting plate spaced apart from said annular flange, a cowl substantially semi-circular in hori- zontal cross section positioned against said supporting plate, and detachable means car- ried by said annular flange for detachably 75 securing said cowl in place.

In testimony whereof I have affixed my signature in presence of two witnesses.

FRANK JAY ANDREWS.
